PRESSING MACHINE FOR COLLARS

Filed Dec. 14, 1937

FIG. 1

UNITED STATES PATENT OFFICE

2,141,051

PRESSING MACHINE FOR COLLARS

Stephen Stadub, Brooklyn, N. Y.

Application December 14, 1937, Serial No. 179,649

5 Claims. (Cl. 223—2)

My invention relates to machines for pressing collars and has particular reference to machines for pressing or ironing shirt collars especially in the process of their manufacture.

My invention has for its object to provide a machine for performing several operations required in the manufacture of shirt collars and particularly their ends or points, the operations being performed manually with the help of pedal operated fixtures. In order to facilitate these operations I mount several fixtures on a table with a plurality of pedals adapted to be operated by operators sitting on stools in front of the machine and using both feet each when it is necessary to simultaneously depress two pedals. Two sets of fixtures are provided, one for inverting sewed collars, and the other for pressing the inverted collars. One machine may have several of such sets so that a number of operators can use a single machine which is preferably made round so as to occupy the least space for a given number of operators.

The collar inverting fixture consists of two pointed rods which are advanced against each other when a collar is placed therebetween, a pedal being used for this movement, connected by a rod with the movable pointed rod.

For pressing the collars I provide a block with an electric heater inside and with a plurality of irons shaped in accordance with the desired form of the collar points, which may be round or pointed. The irons are mounted on rods extending to separate pedals, there being one pedal for each iron. The irons are raised from the heating block by depressing corresponding pedals.

In front of each iron I mount a movable plate for supporting the collar, the plate being movable by a separate pedal for its insertion under the pressing iron.

Other objects and advantages of my invention will be obvious from the accompanying specification and drawing in which—

Fig. 1 is an elevational view of my machine partly in section.

Fig. 2 is a fractional detail view of the heating and pressing members.

Fig. 3 is a top plan view of the machine partly in section.

Fig. 4 is a sectional detail view of the plate moving mechanism.

Fig. 5 is a detail view of the collar inverting mechanism.

Fig. 6 is a detail view of the operative connections between the pressing irons and the pedal.

My machine comprises a table preferably of a round shape 1 mounted on a standard 2 supported vertically on a base plate 3. A heating block 4 is mounted on top of the table or on the upper extension of the standard 2 and consists of a hollow metal box with a flat plate 5 on top and an electric heating element 6 imbedded in an insulation 7. Leads from the element extend to the outside through a detachable plug 8 and socket 9, a switch 10 being used for disconnecting the circuit. A multiple die 11 is fitted on top of the plate 5 and is provided with a number of slots 12 corresponding in shape to the points of collars and to corresponding collar supporting plates 13. Pressing or heating blocks 14 are slidably supported in the slots 12 on the hooked ends of rods 15 passing through the box 4 and the table 1, the lower ends of the rods being connected together by a bar 16 engaged by the end of a pedal 17 pivoted at 18 to a pedal frame 19 mounted on the standard 2.

A cover 20 is mounted on top of the box or block 4 and may be fastened by a screw 21 threaded into the die block 11. Red glass reflecting balls 22 are supported on the cover 20 to indicate that there may be an electric current or heat. The balls may be replaced by red lamps connected in circuit with the switch 10 and adapted to be lighted when the electric heater is connected in circuit. The cover slidably fits over the outer sides of the pressing irons 14 and guides them in their vertical movements.

The collar plates 13 are shaped to correspond to the shape of their respective pressing irons 14 and are adapted to support corners or points of collars 23. The plates 13 are supported on extensions 24 of blocks 25 sliding in guiding tubes 26. The latter are curved over the top of the table 1 and extend downward to the pedal frame 19. The blocks 25 are slidably fitted on curved rods 27 held by their inner ends in plates 28 fastened in the tubes 26. Springs 29 are supported on the curved rods 27 and tend to keep the plates 13 away from the box 14. The plates 28 have slots for chains 30 attached by their ends 45 to the blocks 25 and passing over pulleys 31 supported on shafts 32 at the points of joint between the upper curved portions of the tubes 26 and their lower vertical portions. The chains are connected to rods 33 fastened at their lower ends to the inner ends of pedals 34. The outer ends of the pedals are hinged at 35 to brackets 36 supported on the base plate 3. The pedals 34 are placed side by side with the pedals 17 so that one operator can use both these pedals while 55

sitting on a stool in front of the machine, or he can press both pedals at once by one foot placing it between the pedals.

The tubes 26 have slots 37 for the extensions 24.

5 The curvature of the tubes 26 in their upper portions is such that the plates in their inoperative or outer position extend at an angle upward in order to facilitate placing collars 23 over the pointed ends of these plates.

10 The ironing or pressing blocks 14 normally remain in their lower position by gravity. Springs 38 may be also provided between the bars 16 and the frame 18 in order to accelerate the downward movement of the blocks 14 after they have 15 been raised by the pedals 17.

Additional pedals 39 are provided under the frame 18 hinged at 40 and connected with rods 41 whose upper ends are pivotally connected at 42 with levers 43 pivoted at 44 to the inner walls 20 of boxes 45 suspended from the table. The other ends of the levers 43 engage the lower ends of 25 plungers 46. There are two such plungers in a typical machine as shown although, of course, any desired number of them may be provided 30 with their pedals at the sides of the corresponding die or block 14 and plate 13 assemblies. The ends of the plungers 46 are pointed and are used for supporting points of sewed collars for their inversion when held by the raised points of the 35 plungers against cylinders 47 slidably fitted in the ends of stationary brackets 48 mounted on the table 1. Springs 49 tend to push the cylinders outward. Blunt ends may be provided on similar plungers 50 for round collars.

35 The operation of my machine is as follows. As many operators may be stationed around the machine as there are operative units, so that six men can work on the machine shown in the drawing. Two men work on the inversion of 40 collars and use the plungers 46 and 50 with their pedals 39.

A collar 23 is placed on the end of the plunger 46 or 50, depending on whether it is sharp pointed or round, and the corresponding pedal 39 is depressed thereby clamping the collar against 45 the cylinder 47. The collar can be then inverted in order to place the seam inside. The inverted collar is given to the next operator for pressing. The presser mounts the collar on the end of the plate 13 and depresses both pedals 34 and 17. 50 The pedal 17 raises the corresponding pressing iron 14 as shown at the right in Fig. 2 while the pedal 34 causes the plate 13 with the collar to move into the slot 12 on top of the plate 5 which is maintained hot by the electric heater 6. The operator then shifts his foot to the pedal 34 releasing the pedal 17 so as to allow the block or bar 16 to be moved down by the spring 38 thereby 55 pressing the iron 14 against the collar 23. The iron 14 has been previously heated by the contact with the hot plate 5 so that the collar will be pressed by the spring 38 between two hot surfaces. At the expiration of the required time the operator shifts his foot to the pedal 17 and releases the pedal 34. As a result, the iron 14 becomes raised and the plate 13 with the collar 60 65 becomes withdrawn into the exposed or inoperative position for removing the pressed collar.

70 The operation of inverting collars requires less time than their pressing so that one operator with one plunger can supply inverted collars to two pressers. For this reason the machine is preferably provided with twice as many pressing units as inverting plungers. The operator may 75

use both his feet if he sits on a stool in front of the machine, although it is quite convenient to use but one foot for operating both pedals 17 and 34.

I claim as my invention:

1. A machine for pressing collars comprising a table, a block on the table, means to heat the block, a plate adapted to mount a collar, a tubular guide supported on the table, the upper portion of the guide being curved and extending outwardly from the block, the lower portion extending downward, means to support the plate by the guide, the curvature of the guide being such as to cause the plate to be rigidly inclined upward in the outer position in the guide and to be placed 10 on the block in the inner position, a flexible member extending in the guide from the plate support, a pedal at the lower end of the flexible member, the plate support being adapted to be moved by the pedal through the flexible member, means 15 to guide the flexible member in the tubular guide, and means to press the collar against the block when the collar is placed on the block.

2. A machine for pressing collars comprising a table, a block supported on the table, a plate 25 on the block, means to heat the block, a die on the plate conforming to the shape of a collar, a pressing iron slidably fitted in the die, means to manually move the iron, a cover attached to the upper side of the die, means to guide the outer portion of the iron by the cover, a pointed member adapted to support a collar, means to manually place the member with the collar on the plate between the sides of the die, and means 30 to press the collar by the iron against the plate, 35 the cover having an opening for the insertion of the collar.

3. A machine for pressing collars comprising a table, a block supported on the table, a plate on the block, means to heat the block, a die on the 40 block conforming to the shape of a collar, a pressing iron slidably fitted in the die, means to manually move the iron, a cover attached to the upper side of the die, means to guide the outer portion of the iron by the cover, a pointed member 45 adapted to support a collar, means to rigidly support the collar supporting member at a distance from the block with the point of the member in the raised position for mounting the collar, and means to manually place the supporting member with the collar on the plate between the sides of the die.

4. A machine for pressing collars comprising a table, a block supported on the table, a plate on the block, means to heat the block, a die on the 55 block conforming to the shape of a collar, a pressing iron slidably fitted in the die, means to manually move the iron, a cover attached to the upper side of the die, means to guide the outer portion of the iron by the cover, a pointed member 60 adapted to support a collar, a curved guide extending from the block to the outer side of the table, means to slidably support the collar supporting member on the guide, means to manually move the collar supporting member on the guide 65 for placing the collar on the plate when the iron is raised, and means to retrieve the collar supporting member in the outer position, the guide being adapted to rigidly support the collar supporting member in the outer position with the 70 point of the supporting member raised for mounting the collar.

5. A machine for pressing collars comprising a table, a block supported on the table, a round plate on the block, means to heat the block and 75

the plate, a plurality of dies on the plate for collars, a cover with cylindrical sides supported on the plate with the dies and having openings for inserting the collars, pointed members adapted to support collars, curved guides for the collar supporting members radially extending from the plate to the outer edge of the table, and

means to manually move the collar supporting members on the guides for inserting the members into the openings in the cover and placing them on the plate, the guides being adapted to hold the covers in the outer position with the points raised for mounting the collars. 5

STEPHEN STADUB.
